FIG. 5.

FIG. 8.

FIG. 7.

Inventor,
Benjamin D. Chamberlin

UNITED STATES PATENT OFFICE.

BENJAMIN DAY CHAMBERLIN, OF ROCHESTER, NEW YORK.

WASHING MACHINE.

Application filed September 8, 1922. Serial No. 586,893.

To all whom it may concern:

Be it known that I, BENJAMIN D. CHAMBERLIN, a citizen of the United States, residing at Rochester, in the county of Monroe 5 and State of New York, have invented certain new and useful Improvements in Washing Machines, of which the following is a description.

This invention relates to washing machines and more particularly to washing machines of a compact type adapted particularly for use in apartment houses and other places where the room is limited. One object of my invention is to provide a folding 10 washing machine which is compact and simple to operate; another object is to provide a frame for the machine which can be folded so that the several parts of the machine will be contained in the standard type of stationary wash tub; another object is to provide connections between the several parts of the machine which lend themselves to assembling and disassembling for setting up or folding the compact machine; and other 15 objects will appear from the following specification, the novel features being pointed out in the claims at the end of the specification.

This machine was particularly designed 20 to conserve space and is constructed to fold completely into the standard double wash tub, such as is practically universally used. The shape of the frame and parts are such that a cover or lid can be placed on the tubs 25 to serve as a table when the machine is not in use, as the several parts of my machine can be folded below the level of the top of the tubs, only a very small section of the frame being above this plane.

40 In the drawings, in which like reference characters throughout:

Fig. 1 is a view partly in section through a machine constructed in accordance with and illustrating one embodiment of my invention;

Fig. 2 is a section through the washing machine drum, being taken on line II—II of Fig. 1;

Fig. 3 is a fragmentary elevation of a 50 part of the supporting frame of my machine;

Fig. 4 is a perspective of the frame of my machine;

Fig. 5 is a section through one of the tubs 55 showing part of my machine folded into a tub;

Fig. 6 is a fragmentary view of the tub driving mechanism;

Fig. 7 is a plan view of the driving yoke; and

Fig. 8 is a section of the wringer.

The stationary wash tubs A—B are of the usual type, made of concrete, stone or composition and comprise a rear wall *a*, side walls *b*, *b*, *b*, bottom wall *c* and a slanting front wall *d*. I provide a frame 1, (Fig. 4) having raised portions 2—2 and 3—3 adapted to lie upon the edges of the tubs, so as to leave the major portion of the frame either beneath or parallel to the upper edges *e*—*e* of the tubs. This frame may be held in position in the tubs by means of the set screws 4—4, although the weight alone is sufficient to hold it somewhat less rigidly in place. Bearings 5—5 are provided in tub A 70 for the drum shafts 6 and 12. In tub B there are bearings 7—7 which receive a rod 8 which forms the pintle upon which a table 9 is hinged, to fold into two positions as will be hereinafter more fully described. Thus the main frame consists of two sections 1 and 9 movable relative to each other. These parts may be held together by a latch 70, operated by a handle 71 and normally 75 spring pressed into operative position by a spring 72. When the frames are in operative position, Fig. 3, latch 70 extends over the edge 9^a of section 9 retaining it in position. Pressure on handle 71 against spring 72 permits section 9 to fold to the position 80 shown in Fig. 5.

The washing machine drum consists of two sections 10 and 11; section 10 is shorter than section 11 and of slightly less diameter. Section 10 is provided with a stub shaft 12 85 on one end and 6 on the other. These shafts engage bearings 5 of the frame and also support section 11, as there is at each end of this drum a bearing 13 formed in the heavy metal straps 14. Drum section 11 can, therefore, swing about section 10 into an open position (dashed lines Fig. 2) and into a closed position (shown in full lines same figure.) It should be noted that in this open position one edge 15 of the section 11 90 engages a stop 16 on section 10 to limit its rotation relative to the section 10 in one direction, and a latch 17 pivoted to drum 10 engages a pin 18 on drum section 11, so that the sections form a complete drum when in the closed position. In this way section 11 can be used as a door through which

clothes are placed in the tub, and likewise as a hinged member adapted to reduce the size of the drum sufficiently to fold compactly into a tub. I preferably perforate the drum 5 as indicated at *p*.

The tub as a whole derives its movement through a form of crank movement caused by the mechanism shown diagrammatically in Fig. 6. A gear 19 is affixed to shaft 12 10 and it meshes with a rack 20 which is carried by a pitman rod 22 attached to a crank 23 which is mounted upon a power driven shaft 24. In order to keep the rack and pinion in mesh a floating carrier is used consisting of two plates 25 which swing upon 15 shaft 12 and support two rollers 26 and 27 upon which the under side of rack 20 runs. This carrier rocks as the angle of the pitman alters as will be obvious. The relation of 20 the pinion 19 to rack 20 is such that the drum will revolve one revolution to each reciprocation of the pitman. This relation can be altered at will by merely changing the size of the pinion and the floating carrier 25 above described.

In the upper end of the pitman there is a notch 28 which engages the pin 29 of the crank 23, and is held thereon by a spring latch 30. A cover 31 is hinged at 32 to the frame to protect these parts. It is obvious that the pitman can be easily disconnected at any time by operating the latch.

Shaft 24 is power driven through bevel 35 gears 34 and 35, shaft 36 reducing gears 37 and 38, shaft 39, gear 40 and the worm 41 which is mounted upon a friction collar 42, driven by the collar 43 rotated by the motor 44. This motor may be made to run 40 in either direction and can be reversed while running.

A frame 45 is supported upon the hinged table 9, and is used to carry the parts described in the preceding paragraph as well 45 as to carry the wringer. This consists of rollers 46 and 47, connected rotatively by gears 48 and 49, the former of which is power driven through shaft 50, and bevel gears 51 and 52, the latter being keyed to power shaft 36. The wringer frame 53 is 50 swingingly mounted upon this shaft, moving upon bearings 54 and 55, so that the wringer may be rotated upon shaft 36. From Fig. 8 it will be seen that the upper roller 47 is not carried upon the main wringer frame 53, but by bell crank levers 57 (one at each end) which are pivoted at 58 to the frame bearings 59. A lever 60 is pivoted to a lever 57 and is provided with a toe 61 55 which is pressed outwardly by a block 62 which rests against a spring 63. A pin 64 limits the downward movement of the toe, but by drawing out on the handle 65 (direction of arrow Fig. 8) the toe slips from block 62 permitting roller 47 to raise to 60

dashed line position. This movement makes the wringer safe and in addition can be used when the clothes do not run through the rollers properly. It should be noted that each side of roller 47 is supported by 70 a bell crank lever 57, and that a spring 63 is used on each side to keep the rollers under proper tension. I prefer to use only one operating lever 60 however and to connect both bell crank levers 57—57 together 75 by a shaft 64 so that both bell crank levers will be simultaneously actuated. It is obvious that two handles may be used if desired.

From the foregoing description it will appear that I have provided a washing machine which is fully equipped to do the work of larger machines, but nevertheless, which may be folded into stationary tubs. On one tub the frame folds so that the driving mechanism, motor and wringer can be lowered beneath the top of the tub and on the other side the washing drum itself is made to fold into itself to a position below the top of the tub, so that, if desired, a 90 flat top *M* can be placed over the folded machine.

Having thus described my invention, what I claim as new and desire to secure by Letters Patent is:

1. In a washing machine adapted to be mounted on a stationary tub, the combination of a frame adapted to support a drum, raised portions on the frame to engage the edges of the stationary tub thus suspending the frame beneath the top of the tub, a second frame section, a motor drive mounted on the second frame section, a hinge connecting the two sections, and means adapted to hold the two sections together. 105

2. In a washing machine, adapted to be mounted in a tub, the combination with a frame supported by a tub, of a drum supported by the frame, a second frame hinged to the first frame, and a drum operating 110 mechanism carried by the second frame, and means for disconnecting the drum from its operating mechanism whereby the latter can be folded beneath the top of the tub upon which the frame is mounted. 115

3. In a washing machine adapted to be mounted upon stationary tubs, the combination of a two-part frame, with raised portions on one part of the frame for supporting it in a tub, the other part of the frame having a hinged connection to the first mentioned frame section, being movable to and from a washing tub, a latch adapted to hold the frame together when the second mentioned frame section is moved from the washing tub, a power drive for the washing machine mounted on the hinged section, said hinged section being movable to an operative driving position above the tubs by moving the hinged section of the frame to 120 125 130

a position above the tub, the power drive lying in the tub when the frame is moved about the hinge in a reverse direction.

4. In a washing machine adapted to be mounted upon twin stationary tubs, the combination with a two-part frame, of a washing mechanism carried by one part of the frame in one tub, and a driving motor mounted on the other part of the frame, means for connecting the power drive to the washing mechanism when the former is raised on its frame to an operative position above the tub, said means being disconnectible to permit the motor to lie inside of a tub when moved to an inoperative position.

5. In a washing machine adapted to be mounted upon twin tubs, the combination with a frame supported upon one tub, a washing mechanism mounted thereon, a second frame section hinged to the first mentioned frame section, a motor mounted upon the hinged section, the hinge between the two sections of the frames permitting the motor to be folded to a position in which it will be entirely within one tub, and a fastening device mounted on one frame and adapted to cooperate with the other frame by which the two frames may be held together.

6. In a washing machine adapted to be mounted upon stationary tubs, the combination with a frame adapted to be mounted in one tub, of a hinged frame section supported by the first mentioned frame, and being adapted to move into and out of another

tub, the two frames carrying washing mechanism and a motor, and means for connecting the washing mechanism and the motor to operate together.

7. In a washing machine adapted to be mounted upon twin stationary tubs, the combination with a frame adapted to support the washing mechanism suspended in one tub, of a second frame supported by the first and being movable with respect thereto into and out of an operative position, means for holding the frames together when in an operative position, a motor carried by the second frame section, said motor being positioned above a tub when the frame has been moved to an operative position, and lying inside of a tub when in an inoperative position.

8. In a washing machine adapted to be mounted upon twin tubs, the combination with a main frame, a washing drum revolvably supported therein, a second frame carried by the first mentioned frame being movably connected thereto, a motor mounted on the second frame, the second frame having operative and inoperative positions relative to the first frame, and means for connecting the motor in an operative position in which it is supported by the second frame above the tubs to the washing drum, whereby the motor may revolve the drum.

Signed at Rochester, New York, this 6th day of September, 1922.

BENJAMIN DAY CHAMBERLIN.
